UNITED STATES PATENT OFFICE.

CHARLES PAFF, OF NEW YORK, N. Y.

RAIL-CLIP.

1,330,277.

Specification of Letters Patent. Patented Feb. 10, 1920.

Application filed June 12, 1918. Serial No. 239,570.

To all whom it may concern:

Be it known that I, CHARLES PAFF, a citizen of the United States, and a resident of New York, in the county of New York and 5 State of New York, have invented a certain new and useful Improvement in Rail-Clips, of which the following is a full, clear, and exact specification.

This invention relates to a class of devices 10 adapted to be used in conjunction with car rails.

My invention has for its object primarily to provide a device or clip designed to be employed for fastening rails on railway ties 15 without the use of bolts and the like, and which is especially adapted to be utilized for fastening rails on the form of metallic tie disclosed in my pending application, serially numbered 235,822, filed May 21, 1918. 20 The invention contemplates mainly the provision of a clamping element of substantially a T-shape which is adapted to be inserted through an opening in the above mentioned tie whereby one of its longitudinal 25 arms will be disposed in overlapping engagement on part of one of the edges of the base-flange of the tie and whereby the second longitudinal arm of the clamping element will be spaced above the tie as well as 30 being in alined opposed spaced relation to the overhanging longitudinal arm of a lug of substantially an inverted L-shape which 35 protrudes upwardly from the tie. On the lower end of the vertical arm of the clamping element is a rightangularly protruding 40 extension member or lug arranged so as to engage the underside of the base-flange of the rail, and associated with the clamping element is a key element adapted to be inserted between the tie and the second longitudinal 45 arm of the clamping element as well as being between the tie and its L-shaped lug so as to cause the clamping element to be locked for locking the rail on the tie.

With these and other objects in view the invention will be hereinafter more particularly described with reference to the accompanying drawing forming a part of this specification in which similar characters of 50 reference indicate corresponding parts in all the views, and will then be pointed out in the claim at the end of the description.

In the drawing, Figure 1 is a fragmentary view showing a top plan of a metallic tie 55 and a car rail and the manner of using a

number of my improved clips for fastening the rail on the tie.

Fig. 2 is a detail sectional view, partly in elevation, taken on the line 2—2 of Fig. 1.

Fig. 3 is a detail sectional view taken on 60 the line 3—3 of Fig. 1, and

Fig. 4 is an enlarged view showing a rail and one of the clips in perspective as associated together.

The device or clip has a clamping element 65 10 and a key or locking element 11 adapted to coöperate for fastening a car rail, as 12, on a metallic tie, as 13, which is preferably of a form disclosed in my hereinbefore named pending application for a patent 70 therefor, the tie having in the top plate, as 14, of each of its member 15 and 16 two openings, as 17 and 18, and the openings of each pair are spaced apart at distances corresponding to the width of the base-flange 75 of the rail so that the parts of the members of the tie between these openings will accommodate the base-flange. Protruding upwardly from the top plate of each member of the tie 13 as a part of the edge of each 80 of the openings which are in spaced opposed relation to the base-flange of the rail is a lug, as 20, of substantially an inverted L-shape so that the longitudinal arm 21 of each lug is spaced above the top plates of 85 the members of the tie and so that the free edge of the longitudinal arm is disposed toward the rail in overhanging arrangement above the openings.

The clamping element 10 is preferably of 90 substantially a T-shape to provide a vertical arm 22 and two alined arms 23 and 24 which are disposed longitudinally in opposite directions from the top of the vertical arm. The vertical arm 22 of the T-shaped clamping element is of a slightly greater length than the combined thickness of the top plate 95 14 of each of the members 15 and 16 of the tie and the base-flange 19 of the rail, and the longitudinal arm 23 of the clamping element 100 is preferably somewhat wider than the longitudinal arm 24. The vertical arm 22 of the clamping element is adapted to be disposed through one of the openings 17 and 18 of one of the members of the tie in close 105 juxtaposition to the base-flange of the rail so that the longitudinal arm 23 of the clamping element is in overhanging engagement on the top of the base-flange of the rail. Protruding rightangularly from the lower 110

end of the vertical arm 22 in a direction similar to the projection of the arm 23 is an extension member or lug 25 which is adapted to closely engage the underside of the top 5 plate of the member of the tie when the vertical arm of the clamping element is disposed in one of the openings 17 and 18. When the clamping element is thus arranged on the tie and rail the arm 24 of the 10 clamping element will be in spaced opposition to one of the lugs 20 of the tie, and the locking element 11 is then employed to lock the clamping element to the tie.

The key or locking element 11 has a substantially rectangular body part or plate 26 which is wedge shaped and somewhat longer than the lengths of the lugs 20 of the tie as well as being somewhat longer than the clamping element, and this body 15 part or plate is of a thickness so as to fit snugly in the space between the top plate of the member of the tie to which it is applied and the lug 20 of the tie and arm 24 of the clamping element. One end of the 20 rectangular plate 26 is bent upwardly in the fashion of a hook, as 27, which is formed so that its entrance will accommodate 25 one end of the arm 24 of the clamping element as well as accommodating one end of the longitudinal arm 21 of the lug 20, the free end of the hook 27 thus being 30 adapted to be disposed in overlapping arrangement on the clamping element and on the lug of the tie when the body part or 35 plate 26 of the locking element is disposed under these parts of the clamping element and tie.

To employ the clip for fastening a car rail on the tie the rail is arranged crosswise 40 of the top plates 14 of the members 15 and 16 of the tie so as to be disposed between the openings 17 and 18 at one end of the tie. One of the clamping elements is then disposed 45 in each of the openings of the tie so that the vertical arm 22 of each clamping element protrudes through one of the openings, and each clamping element is also ar-

ranged so that its arm 23 will overlap the base-flange of the rail, while the arm 25 of each clamping element engages the part of 50 the top plate of the tie which is under the rail. The locking element 11 of the clip is then applied by forcing its plate 26 between the top plate of the tie and the arm 24 of the clamping element as well as between 55 the top plate and the arm 21 of the lug 20 of the tie so that one of the ends of the arm 24 and arm 21 will be clamped in the hook 27 of the locking element, as shown in Fig. 4, the lug 20 being the one in 60 opposed relation to the clamping element. Thus I provide a simple and efficient clip whereby railway rails may be effectually fastened on the metallic tie.

In the foregoing description I have embodied the preferred form of my invention, but I do not wish to be understood as limiting myself thereto, as I am aware that modifications may be made therein without departing from the principle or sacrificing any 70 of the advantages of this invention, therefore I reserve to myself the right to make such changes as fairly fall within the scope thereof.

Having thus described my invention, I 75 claim as new and desire to secure by Letters Patent:—

In a rail clip, a key element comprising a plate adapted to be removably inserted under one of the cross-arms of a substantially T-shaped clamping element as well as under a bent lug provided on a metallic tie when the cross-arm of the element and the lug are in opposition, and a hook shaped member on one end of the plate for engaging 85 the lug and the cross-arm of the clamping element.

In testimony whereof I affix my signature in the presence of two witnesses.

CHARLES PAFF.
